CLAIM

We claim the ornamental design for a remote control, as shown and described.

DESCRIPTION

FIG. 1 is a perspective view of the claimed design;
FIG. 2 is a front view of the claimed design shown in FIG. 1;
FIG. 3 is a rear view of the claimed design shown in FIG. 1;
FIG. 4 is a side view of the claimed design shown in FIG. 1;
FIG. 5 is another side view of the claimed design shown in FIG. 1;
FIG. 6 is a top view of the claimed design shown in FIG. 1; and,
FIG. 7 is a bottom view of the claimed design shown in FIG. 1.
The broken lines in the drawing views show portions of the remote control that forms no part of the claimed design.

1 Claim, 5 Drawing Sheets
